AUTOMATIC TOY MACHINE GUN

Homer C. Douglas, Kansas City, Kans., assignor to T. R. Chamberlain, Kansas City, Kans.

Application February 10, 1951, Serial No. 210,406

10 Claims. (Cl. 42—57)

This invention relates to toy cap guns adapted to successively fire a number of caps through employment of a conventional cap tape, the primary object being to provide in an automatic repeater-type machine gun, means for retarding rotation of certain of the parts thereof taking the form of a governor whereby to control the speed of firing of successive caps.

It is the most important object of the present invention to provide a toy machine gun having means for feeding a cap tape, together with a swingable firing hammer, there being a combination governor and hammer actuating assembly forming a part of the gun that includes a member swingable with respect to the shaft for rotating the same into and out of engagement with a friction plate whereby to retard rotation of the shaft and actuate the firing hammer that is disposed in the path of travel of the swingable governor member.

Another important object of the present invention is to provide a toy machine gun that includes structure adapted both for feeding a cap tape and for actuating the firing hammer of the gun upon release of the structure through trigger mechanism, the aforesaid governor including a rotatable device having a swingable part that moves away from its mounting shaft by centrifugal force.

It is an important object of this invention to provide in a toy machine gun, a combination governor and actuating means for the firing hammer thereof that includes an arcuate friction plate, together with a member that is mounted for rotation within the confines of the friction plate and swingable thereagainst through centrifugal force to retard or brake the rotation thereof.

A further object of this invention is to provide an actuating lug for the firing hammer on the swingable member just mentioned that automatically moves into engagement with a part of the hammer without the confines of the friction plate to successively actuate the hammer once for each revolution of the governor.

It is a still further important object of the present invention to provide a combination governor and hammer actuator of the above mentioned character formed and disposed to assume a resting position at the end of each operation and upon release of the trigger of the gun, which will assure immediate operation to fire the caps upon pulling of the trigger in one direction in timed sequence and without omitting any of the caps of the tape.

Other equally important objects include many novel details of construction, all of which will be made clear or become apparent as the following specification progresses, reference being had to the accompanying drawings, wherein:

Figure 1 is a side elevational view of an automatic toy machine gun made pursuant to my present invention.

Fig. 2 is a cross-sectional view taken on irregular line II—II of Fig. 6.

Fig. 3 is a cross-sectional view taken on line III—III 70 of Fig. 6 looking in the direction of the arrows.

2

Fig. 4 is a cross-sectional view taken on irregular line IV—IV of Fig. 6.

Fig. 5 is a fragmentary, cross-sectional view taken on line V—V of Fig. 6.

Fig. 6 is an enlarged, fragmentary, side elevational view showing the drum magazine with its cover removed.

Fig. 7 is a cross-sectional view taken on line VII—VII of Fig. 6.

Fig. 8 is a fragmentary, cross-sectional view taken on irregular line VIII—VIII of Fig. 2 looking in the direction of the arrows.

Fig. 9 is a fragmentary, side elevational view, parts being broken away and in section to illustrate the trigger mechanism of the gun.

Fig. 10 is a cross-sectional view similar to Fig. 3 illustrating the combination governor and hammer actuating assembly intermediate the ends of its path of travel; and

Fig. 11 is a cross-sectional view similar to Figs. 3 and 10 showing the hammer actuating portion of the governor in a position ready to strike a part of the firing hammer.

While the automatic toy sub-machine gun illustrated in Fig. 1 of the drawings has been formed to simulate the well-known Thompson machine gun, it will hereinafter become clear that the broad principles of the invention may well be incorporated within toy gun designs having configurations differing from those shown in the drawings. In the present gun however, there is provided a stock 12 provided with a depending hand-grip 14 and a trigger 16 adjacent the hand-grip 14 and mounted for swinging movement through the medium of a pivot pin 18.

Trigger 16 is held biased at one end of its path of travel opposite that illustrated in Fig. 9 of the drawings by means of a spring 20 housed within a portion of the stock 12 above pivot point 18 and having connection at that end thereof opposite to trigger 16 by means of a fastening element 22 (see Fig. 1). A second hand-grip 24 is mounted on a barrel 26 intermediate the ends thereof which is in turn secured directly to an outermost plate 28 forming a part of a drum magazine broadly designated by the numeral 30.

A second outermost plate 32 in opposed relationship to the plate 28 and also forming a part of the magazine 30 rigidly receives the stock 12 and its associated parts.

Plates 28 and 32 are preferably circular, as are three discs 34, 36 and 38 disposed within the magazine 30 in parallelism with the plates 28 and 32. All of the discs just mentioned, as well as the end plates 28 and 30 are substantially fully enclosed by an annular wall 40, completing the magazine 30. Wall 40 has an annular flange 41 against which plate 28 bears and an outlet opening 42 formed therein for receiving discharged caps as will hereinafter be made more clear. Disc 34 is spaced from the plate 28 to provide a chamber 44 for receiving an actuating spring 46 coiled about a center shaft 48 and having one end thereof secured to shaft 48 in any suitable manner as illustrated in Fig. 7 of the drawings. The opposite, outermost end 50 of the spring 46 is suitably secured to plate 28 and disc 34. Discs 34 and 36 are in face-to-face engagement and a space between discs 36 and 38 presents a second chamber 52 for receiving the governor-hammer actuating mechanism 53 illustrated most clearly in Figs. 3, 10 and 11 and hereinafter more fully described. Disc 38 and plate 32 are spaced to present a chamber 54 that receives a roll of caps 56, a firing hammer 58, a latch member 60 and other associated parts illustrated in Fig. 2 of the drawings. Obviously, suitable spacers are provided within chambers 44, 52 and 54 and a small block 62 (Fig. 6) within chamber 54 and secured to disc 38, serves to mount a hinge 64 for swingably securing the plate 32 to the disc 38.

A spring latch 66 diametrically opposed to hinge 64,

releasably holds the stock 12 and the plate 32 against swinging movement away from a position where plate 32 is housed within annular wall 40. The shaft 48 that traverses the magazine 30 is rotatably mounted in plate 28 and discs 34, 36 and 38 and an opening 68 (Fig. 7), receives the proximal end of shaft 48 and permits the aforementioned swinging movement of plate 32 toward and away from its normal position shown in Fig. 6 of the drawings. The plate 28 and disc 34 are joined for rotation as a unit with barrel 26 relative to stock 12, plate 32, discs 36 and 38 and wall 40, which are also interconnected. Consequently, rotation of barrel 26 with respect to stock 12 in one direction, winds the spring 46 and counterrelative rotation is prevented by a spring-loaded dog 67 swingably mounted within a cavity 69 in plate 36 and biased toward the disc 34. Disc 34 has a cavity formed therein (not shown) presenting a shoulder for receiving the dog 67.

A gear 70 mounted on shaft 48 for rotation therewith and disposed within the chamber 52 is constantly in mesh with a small pinion 72 also disposed within chamber 52 and secured directly to a stub shaft 74 rotatably carried by the disc 38. Shaft 74 has a lateral extension 76 thereon at that end thereof opposite to the pinion 72 and within the chamber 54.

The roll of caps 56 of conventional character in that the same comprise a tape of successive explosive charges, is rotatably mounted on a laterally extending pin 78 on disc 38 within chamber 54, and the tape 56 is threaded around a sprocket drum 80 secured to shaft 48 for rotation thereby within the chamber 54, tape 56 thence passing through the opening 42 in annular wall 40. After winding of the spring 46, shaft 48 is held against rotation thereby through the medium of the latch 60 engaging the projection 76 in the manner illustrated in Fig. 2 of the drawings. Latch 60 is pivotally mounted to the disc 38 within chamber 54 as at 82 and is substantially Z-shaped, presenting a leg 84 on that side of pivot 82 opposite to extension 76 that is engaged by the innermost end of trigger 16 as shown in Fig. 9 of the drawings when the latter is swung on pivot 18 against the action of spring 29 whereby to cause the latch 60 to swing on pivot 82 out of the rotative path of travel of extension 76 on shaft 74. Latch 60 is yieldably biased to that end of its path of travel shown in Fig. 2 of the drawings by a spring 86.

The hammer 58 is substantially U-shaped and has one of its legs pivotally secured to the disc 38 by means of a pin 88 for swinging movement toward and away from the drum 80. A spring 90 yieldably holds the hammer 58 biased away from the drum 80.

A slot 92 is formed in the disc 38 for receiving a laterally extending pin 94 on that leg of hammer 58 opposite to pivot 88, which pin 94 extends into the chamber 52 in the manner illustrated in Fig. 8 of the drawings. A pair of spaced-apart guides 96 and 98 secured to the disc 38 within the chamber 54 on opposite sides of the drum 80, serve to direct the perforated tape 56 properly around the drum 80 to the discharge opening 42. Guide 98 is provided with a lip 100 to receive the inner end of tape 56 as it leaves pin 78 and causing the tape 56 to properly unroll because of its tendency to maintain the rolled condition shown in Fig. 2 of the drawings.

A third guide plate 102 cooperates with the guide 96 in presenting a tape-receiving channel 104 within the chamber 54 and registering with the outlet 42. Tape 56 is guided to the passage 104 by plate 106 that is pivotally mounted as at 108 on the disc 38 and held biased toward drum 80 by a spring 110 to hold the tape 56 on drum 80. However, when the plate 106 is swung on pivot 108 against the action of spring 110, thereby presenting a space between plate 106 and drum 80 as shown in Fig. 2, tape 56 may be easily threaded over drum 80.

The device 53 shown most clearly in Figs. 3, 10 and 11 includes a segmental plate-like section or element 112 that is secured directly to the shaft 74 between pinion 72 and

plate 38, all within chamber 52. A second arcuate section or control member 114 is pivotally secured to the section 112 as at 116 for swinging movement with respect thereto on an axis that is parallel with the axis of rotation of shafts 74 and 78 and with the axis 88 for swingably mounting the hammer 58. It is noted that assembly 53 is disposed adjacent the pin 94 within chamber 52 and a lug 118 extends from the section 114 radially with respect to the shaft 74 for striking the pin 94 as the device 53 is rotated by shaft 74. Outward swinging movement of the section 114 on the pivot pin 116 by centrifugal force, is limited throughout a substantial portion of the distance of rotation of lug 118 by an arcuate friction plate 120 secured to the disc 38 in concentric relationship with the axis of rotation of shaft 74. Notable in Figs. 3, 10 and 11 is the way in which friction plate 120 is open at arcuate slot 92 in disc 38 and the projecting pin 94 on the hammer 58.

When the gun is in the normal standstill position, the various parts within the magazine 30 are arranged relatively as illustrated in Figs. 2 and 3 of the drawings. In order to place energy in the spring 46 to impart rotation to shaft 48 and accordingly to the shaft 74, the barrel 26 is rotated relative to the stock 12 and counter-rotation is prevented by the dog 67 and the corresponding receiving cavity therefor, formed in that face of disc 34 bearing against disc 36. Since latch 60 normally is in a position for receiving the lateral extension 76 on shaft 74, no operation takes place until actuation of trigger 16. When the latter is pulled to the position illustrated in Fig. 9 against the action of spring 29, latch 60 will be caused to swing on its pivot 82 to release the extension 76. Spring 46 thereupon operates to rotate the shaft 48 which also rotates drum 80 and feeds the tape 56 from pin 78 into the passageway 104. Rotation of shaft 48 also rotates the gear 70 and accordingly, the pinion 72 and as long as the trigger 16 is held depressed, the extension 76 will be free to rotate in the direction indicated by the arrow in Fig. 2 of the drawings. Such continued rotation of shaft 74 will cause the governor assembly 53 to likewise rotate in the direction shown in Figs. 3, 10 and 11. As the sections 112 and 114 rotate within the confines of friction plate 120, centrifugal force will cause the section 114 to swing outwardly away from the axis of rotation of shaft 74 until the lug 118 comes into frictional contact with the inner face of the plate 120. Such "drag" of the lug 118 on plate 120 retards the speed of rotation of the drum 80 and of the entire governor assembly 53. Figure 10 of the drawings illustrates the position of the lug 118 bearing against the plate 120 intermediate the ends of its path of travel. As soon as the lug 118 reaches a position where section 114 may swing outwardly without hindrance by plate 120, lug 118 will move to a position as shown in Fig. 11 of the drawings where it will strike the pin 94. Thus, there is a momentary stoppage of rotation of the governor 53 when the lug 118 strikes pin 94 and carries the same to one end of the slot 92. Such movement of pin 94 swings the hammer 58 with force against an aligned cap on tape 56 whereupon firing takes place.

As soon as the lug 118 slips from the pin 94 under force of the spring 46 while trigger 16 is held in the condition shown in Fig. 9 of the drawings, lug 118 will again move into frictional engagement with the plate 120 and the hammer 58 will return to its normal position shown in Fig. 2 under the influence of spring 90. By careful arrangement and choice of size and configuration of extension 76, the lug 118 will always come to rest substantially as illustrated in Fig. 3 of the drawings, irrespective of its particular position at the time of release of trigger 16. Consequently, whenever the gun is placed in operation, sufficient force will be built up in the assembly 53 to actuate hammer 58 on the first revolution of the lug 118, from the position shown in Fig. 3 to the position shown in Fig. 11, and all caps forming a part of the tape 56, will be fired.

Thus, in all respects the toy machine gun hereof has been made for rapid firing of successive caps that are readily available on the open market and provision has been made for accurate timing as well as to assure that each and every cap receives a blow from the hammer 58 of sufficient force to cause firing thereof if the cap is otherwise capable of exploding under such force. Also, by virtue of the guiding means 96, 100, 102 and 106, the tape 56 will pass from the pin 78 to the drum 80 and thence to outlet 42 by way of passage 104 without difficulty from the strandpoint of jamming or piling up within the chamber 54. Even the curled end of the tape 56 moving from pin 78 will be caught by the lip 100 and unwound as drum 80 continues to operate, assuring firing of every cap of a roll 56 thereof.

Manifestly many details of construction coming within the spirit of this invention may be changed or modified to provide equivalents for the broad concepts hereof and it is, therefore, desired to be limited only by the scope of the appended claims.

Having thus described the invention what is claimed as new and desired to be secured by Letters Patent is:

1. In a toy cap gun having cap tape-feeding means, cap firing means, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft for rotation therewith, said member being pivotally mounted for outward swinging movement away from said second shaft and into frictional engagement with said plate in response to centrifugal force as the second shaft and member rotate.

2. In a toy cap gun having cap tape-feeding means, cap firing means including a movable hammer, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft for rotation therewith, said member being pivotally mounted for outward swinging movement away from said second shaft and into frictional engagement with said plate in response to centrifugal force as the second shaft and member rotate, said hammer being within the path of travel of said member for movement thereby as the member rotates.

3. In a toy cap gun having cap tape-feeding means, cap firing means including a swingable hammer, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft for rotation therewith, said member being pivotally mounted for outward swinging movement away from said second shaft and into frictional engagement with said plate in response to centrifugal force as the second shaft and member rotate, said member having a lug thereon, there being a pin on the hammer within the path of travel of said lug whereby swinging movement is imparted to the hammer by said member.

4. In a toy cap gun having cap tape-feeding means, cap firing means including a swingable, spring-loaded hammer, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft

5 for rotation therewith, said member being pivotally mounted for outward swinging movement away from said second shaft and into frictional engagement with said plate in response to centrifugal force as the second shaft and member rotate, said member having a lug thereon, there being a pin on the hammer within the path of travel of said lug whereby swinging movement is imparted to the hammer in one direction against the action of its spring during each revolution of the member.

10 5. In a toy cap gun having cap tape-feeding means, cap firing means including a swingable hammer, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft for rotation therewith, said member being pivotally mounted for outward swinging movement away from said second shaft and into frictional engagement with said plate in response to centrifugal force as the second shaft and member rotate, said member having a lug thereon, there being a pin on the hammer within the path of travel of said lug whereby swinging movement is imparted to the hammer by said member, said pin being in spaced parallelism with the second shaft, said lug being radially disposed relative to the second shaft.

15 6. In a toy cap gun having cap tape-feeding means, cap firing means including a swingable hammer, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft for rotation therewith, said member being pivotally mounted for outward swinging movement away from said second shaft and into frictional engagement with said plate in response to centrifugal force as the second shaft and member rotate, said member having a lug thereon, there being a pin on the hammer within the path of travel of said lug whereby swinging movement is imparted to the hammer by said member, said pin being in spaced parallelism with the second shaft, said lug being radially disposed relative to the second shaft.

20 7. In a toy cap gun having cap tape-feeding means, cap firing means including a swingable, spring-loaded hammer, and structure including a first rotatable shaft for driving said feeding means and a second rotatable shaft operably coupled with said first shaft for driving said firing means to fire a succession of caps; a governor for retarding the operation of said structure, said governor including a friction plate; a control member; and means attaching the member to said second shaft for rotation therewith, said member being pivotally mounted for outward swinging movement away from said second shaft and into frictional engagement with said plate in response to centrifugal force as the second shaft and member rotate, said member having a lug thereon, there being a pin on the hammer within the path of travel of said lug whereby swinging movement is imparted to the hammer by said member, said pin being in spaced parallelism with the second shaft, said lug being radially disposed relative to the second shaft.

25 8. In a toy cap gun having cap tape-feeding means and cap firing means including a swingable hammer, structure for driving said feeding means and said firing means to fire a succession of caps, said structure including a first rotatable shaft coupled with said feeding means; a second rotatable shaft coupled with said firing means; a control member; and means attaching the member to said second

30 9. In a toy cap gun having cap tape-feeding means and cap firing means including a swingable hammer, structure for driving said feeding means and said firing means to fire a succession of caps, said structure including a first rotatable shaft coupled with said feeding means; a second rotatable shaft coupled with said firing means; a control member; and means attaching the member to said second

shaft for rotation therewith, said member being pivotally mounted for outward swinging movement away from said second shaft, said hammer being within the path of travel of said member for movement thereby as the member rotates.

9. A toy machine gun comprising a cap tape feeder; a movable cap-firing hammer; and means for moving said hammer including an element rotatable throughout a complete revolution and having a control member swingably mounted thereon and rotatable therewith throughout said complete revolution, said hammer being within the path of travel of said member as the element rotates, whereby the hammer is struck and thereby actuated once during each cycle of revolution of the element.

10. A toy machine gun as set forth in claim 9 wherein

15 is provided means within the path of travel of said member and disposed for frictional engagement thereby for retarding the speed of rotation of said member.
